CLAIM

The ornamental design for a truing tool for a grindstone, as shown and described.

DESCRIPTION

FIG. 1 is a front side view of the invention;

FIG. 2 is a top plan view of the invention;

FIG. 3 is a first end view of the invention;

FIG. 4 is a second end view of the invention;

FIG. 5 is a rear side view of the invention;

FIG. 6 is a bottom plan view of the invention;

FIG. 7 is a rear perspective view of the invention; and,

FIG. 8 is a bottom perspective view of the invention.
